UNITED STATES PATENT OFFICE.

CHARLES A. GRIFFITH, OF PRUDEN, TENNESSEE.

MINE-CAR-DUMPING APPARATUS.

1,111,830.

Specification of Letters Patent. Patented Sept. 29, 1914.

Original application filed May 17, 1909, Serial No. 496,560. Divided and this application filed December 27, 1910, Serial No. 599,241. Renewed May 14, 1914. Serial No. 838,616.

To all whom it may concern:

Be it known that I, CHARLES A. GRIFFITH, a citizen of the United States, residing at Pruden, in the county of Claiborne and State 5 of Tennessee, have invented certain new and useful Improvements in Mine-Car-Dumping Apparatus, of which the following is a specification, reference being had therein to the accompanying drawing.

10 My improvement relates particularly to mine tipples or apparatus applied to a mine railway track for tilting cars endwise for the discharge of their loads while traversing said track.

15 The object of the improvement is to provide such an apparatus in automatic or semi-automatic form and adapted to rapid operation and simple and durable construction.

In the accompanying drawings, Figure 1 20 is a plan of an apparatus embodying my improvement; Fig. 2 is an elevation of the same apparatus; Fig. 3 is a larger sectional elevation of the portion of the apparatus shown in the right hand part of Fig. 2; Fig. 4 is a section on the line 4—4

25 of Fig. 3, showing a transverse shaft and parts thereto attached, the function of which is to engage and hold the car while it is being tilted and thereafter release it and allow it to move forward on the track; Fig. 30 5 is a detail section of a latch supporting bracket on the line 5—5 of Fig. 3, looking toward the left; Fig. 6 is a section on the line 6—6 of Fig. 3, looking toward the left;

35 Fig. 7 is a horizontal section on the line 7—7 of Fig. 3; Fig. 8 is a section on the line 8—8 of Fig. 3, looking in the direction of the arrow; Fig. 9 is a sectional detail showing 40 the attachment of one of the guard rails to the adjacent main rail.

The movement of filled cars is from right to left.

Any suitable trestle or frame-work may 45 be used for supporting the track at the desired height to make room for dumping plates, screens, etc. below the track. In the form shown in the drawings, the frame-work is wide enough to also support a return track for empty cars.

50 A, A are posts upon the upper ends of which rest cross beams or caps B; and on said caps rest longitudinal beams or sills C. Upon said sills rests platform flooring D, excepting along the dumping station, (the 55 portion of the main track at which the cars are to be tilted for the discharge of their

loads through the spaces between said sills) and along the main track at the right of said dumping station. The posts A, A, are shortened slightly from the left to the right so as to make the return track supported by 60 the sills C, decline sufficiently toward the right to cause the empty cars to run thereon toward the right by gravity.

At the right or in front of the dumping 65 station, short posts E, rise from the caps B, and transverse caps F, rest upon said posts. And upon said caps rest longitudinal beams or sills, G. Upon said beams rests flooring H, which supports the rails, I, I, forming the 70 main track. In order that said track may decline toward the dumping station so as to allow the filled cars to run thereon by gravity toward the dumping station, the short posts E, are made lower and lower from 75 right to left, and by means of said posts this portion of the track is elevated above the flooring D, which is at the opposite side of the dumping station, in order that the portion of the track passing the dumping station 80 may be steep.

Near the middle of the dumping station is a cross beam, K, resting upon the longitudinal beams C, and at the left of the dumping station is a similar cross beam L, 85 also resting upon the longitudinal beams C. But the cross beam K, is preferably a little higher than the cross beam L, in order that the track rails I, may descend slightly in going from the cross beam K, to the cross beam L.

The track rails I, extend from the platform H, across the dump opening in the frame at the dumping station to the platform D, at the left of said opening, and 95 thence along said platform. After leaving the platform H, said rails are straight for a short distance and then extend downward at a steep grade to meet the cross beam K, as shown in Fig. 3. This steep portion of said 100 rails between the platform, H, and the cross beam K, supports the car S, while the load is being discharged, and such portion of said rails must be of sufficient inclination to allow the contents of the car to slide by gravity 105 out of the forward or left hand end of the car body when the adjacent end board s, has been raised as will be hereinafter described. In the opening between the cross beams, K and L, and the longitudinal sills C, is an 110 inclined dumping plate M, which leads to a screen N. Inasmuch as such dumping plates

and screens have heretofore been used, I deem it unnecessary to here describe them in detail. Along the inner side of such steep portion of each of the rails I, I, is a guard rail J, supported from the adjacent rail I, by brackets j, (see Figs. 1 and 9). The purpose of said guard rails is to prevent the cars from shifting laterally far enough to make the car wheels fail to engage the 10 curved arms 7, hereinafter described.

Associated with the track formed by the track rails I, is a return track O, suitable track switches being located between the dumping station and the left hand end of 15 the main track, as will be described below. And the left hand end of the main track is curved upward, as shown in Fig. 2, to arrest the forward movement of the car coming from the dumping station after allowing the 20 car to rise sufficiently to cause it to run backward and pass the switch and enter upon the return track.

The inner rail O, of the return track extends beneath the adjacent rail I, of the 25 main track and approaches the other rail I, of the main track. A switch point P, extends obliquely toward the left from the end of said rail O, to said rail of the main track. Said point is hinged at p to the end of the rail O, of the return track and is pressed against the adjacent rail of the main track by a spring p¹, on a bolt p². As will be readily understood from the drawings, the wheels of a car while passing toward the left on said 35 main rail will push said point away from said main rail.

Immediately at the right of the inner rail O, the main track rail I, is cut obliquely, approximately parallel to said rail O, so that 40 the ends of said cut overlap, and near the other rail O, said rail I, is again cut. The section I¹, of the rail I, thus freed is hinged at its left hand end by means of an upright bolt or pintle Q. And a contracting coiled 45 spring R, located between the two rails I, I, and fixed by one end to the platform D, and attached by the other end to said freed section of the adjacent rail I, draws the right hand end of said freed section yieldingly 50 against the adjacent overlapping rail end. At the left of the hinge formed by the pintle Q, there is a space between the rail I and the outer rail O, sufficient to permit the passing of the flanges of the car wheels.

55 It will now be understood that when a car stands upon the extreme left hand portion of the rails I, I, leftward of the switch point P, and is allowed to move rightward by gravity, the wheels will enter upon the rails O, O, the wheels on the inner of said rails pushing aside the hinged sections I¹, of the rail I, which extends across or over the inner rail O. Thus the two tracks are adapted for the movement of the cars by gravity from 60 the right toward the left, on the main track,

and then from the left toward the right on the return track. Tracks providing for such movement of the cars past a dumping or tipple have heretofore been used. My improvement is limited to use with mechanism by 70 means of which the car is stopped, in the inclined position, and made to discharge its load at the dumping station and then released and allowed to proceed. This car-stopping mechanism comprises one or more 75 movable members having a path extending from a point outside of the car path into said path in the direction opposite the direction of movement of the cars. In the particular form shown in the drawings, there are 80 two such members consisting of curved arms rigidly mounted on a rock shaft located below the track rails, or said arms and said shaft may be regarded as together constituting such a stopping member.

The rock-shaft 1, is located below the rails I, I, and rests in bearings 2, secured by ears 3, and bolts 4 to said rails. At the outer side of each of said rails a sleeve 5 surrounds said shaft and is immovably secured thereto 90 by a key 6; and from each of said sleeves rises a curved arm 7 rigid with said sleeve, so that said arms can turn only when said shaft turns. The inner portion of said arm is directed toward the right and is of proper 95 size and form to receive the forward portion of the forward wheel of a car moving toward the left on the rails I, I, after said arms have been turned toward the left. But, in their normal position, said arms are 100 turned far enough to the right to cause their upper ends to bear against the rims of the forward car wheels approximately horizontally opposite the hubs of said wheels, as 105 shown in Fig. 2. The movements of said arms, and the rock shaft 1, are controlled by means of a segment, an arm, and a spring mounted upon one end of the rock shaft next to the adjacent sleeve 5. Such arm 8 is mounted radially on the sleeve 9, which surrounds the shaft 1, and is secured immovably thereby by means of a key 10. Said sleeve 9 is loosely surrounded by a sleeve 11, between the arm 8, and the adjacent sleeve 5. And said sleeve 11, supports a rigid 115 quadrant plate 12, which is parallel to the arm 8, and has in its periphery a notch 13, and on its periphery at its upper corner, a stop 14, and on its periphery at its lower corner, a stop 15. Above the arm 8, and on 120 the adjacent face of said quadrant plate is a stop 16, which limits the upward movement of said arm.

A contracting coiled spring 17, is secured by one end to a wrist 18, on the arm 8, and by 125 its other end to a wrist 19, on the lower corner of the quadrant plate 12.

When the curved arms 7 are not engaged by the wheels of a car, the spring 17, contracts and draws the arm 8, toward the wrist 130

19, whereby the rock shaft is partially rotated and caused to carry the curved arms 7, toward the right or clockwise, as viewed in Figs. 2 and 3. Said quadrant plate is normally held in the lower right hand quarter of the circle, the position shown in Figs. 2 and 3, by means of a latch bolt 20, entering said notch 13. Said latch bolt is held slidably in a horizontal sleeve 21, supported by a bracket 22, which bracket extends rigidly downward from the adjacent rail I, to which it is secured by means of bolts or rivets 23. A contracting coiled spring 24, is secured by one end to the bracket 22, at 25 and by its opposite end to a standard 26, rising from the latch bolt 20, at the right of the sleeve 21. Through such connection, said spring tends to draw said latch bolt toward the left. At its right hand end, said latch bolt has an upturned hook 27, which engages a similar downturned hook 28, on an approximately horizontal shift bar 29. The left hand portion of said bar extends through a stationary sleeve 30, secured to an adjacent portion of the framing, while the right hand end of said bar is hinged at 31 to the upright lever 32. The lower end of said lever is hinged at 33 to the frame structure.

At the left of the sleeve 30, an expanding coiled spring 34, surrounds the shift bar 29, and bears by its right hand end against said sleeve while its left hand end bears against a cross pin 35, in said shift rod, whereby said spring is adapted to normally press said shift rod toward the left.

The relative arrangement and dimensions of the latch bolt, shift bar, and springs 24 and 34, are such as to put the hooks 27 and 28, into engagement with each other when the lever 32, is free and the latch bolt rests in the notch 13.

The operation of this mechanism for holding the car on the steep inclined portion of the track rails I, I, is as follows: Assuming that the parts are in their normal position—the latch bolt in the notch 13, of the quadrant plate 12, whereby said quadrant plate is locked immovably, and the coiled spring 17, has contracted so as to lean the curved arms 7, toward the right—a loaded mine car S, is allowed to run by gravity over the rails I, I, from the right toward the left until the front wheels W, of said car bear against the curved arms 7, and press them leftward, turning the rock shaft 1, and the arm 8, in opposition to the spring 17, the latter being lengthened, until said arm 8, bears against the stop 16, on the upper edge of the quadrant plate, whereby said rock shaft and the curved arms 7, are locked against further movement with reference to said quadrant plate. The latter has already been locked by the latch bolt 20. Hence the curved arms 7,

stand immovably in the path of the wheels 65 of the car and hold the car immovably at the same inclination as the inclination of the portions of the rails I, I, upon which the wheels of the car then rest. And in this position the car will remain so long as the 70 quadrant plate remains locked. By now moving the lever 32, toward the right, the shift bar 29, draws the latch bolt 20, toward the right and out of engagement with the quadrant plate, whereby the latter is free 75 to turn upward (contra-clockwise) until the lower stop 15, on said plate abuts against the latch bolt sleeve 21. This allows the curved arms 7, to move leftward and downward until they reach the level of the upper 80 faces of the rails I, and leave a clear way for the car wheels to move forward on said rails. After said wheels have passed, the spring 17 again contracts and draws the arm 8, toward the wrist 19, on the quadrant 85 plate, whereby the normal relation between said plate and the curved arms 8, is restored; and at the same time the weight of the quadrant plate, arm 8, and coiled spring 17, turn said rock shaft clockwise, said plate, arm, and spring going downward, until the notch 13 is opposite the latch bolt, whereupon said bolt slips into said notch and again locks said plate. The stop 14 arrests the downward movement of the quadrant plate when said notch is opposite the latch bolt.

At each side of the dumping station is an approximately horizontal and stationary bar 36, supported on standards 37, having their 100 lower ends secured to the adjacent rail I. The function of said bars is to support the forward end gate s, of the car while the forward end of the car descends, whereby said end of the car is left open for the 105 escape of the contents of the car by gravity. Each end of said end gate is secured to one end of an arm s², while the opposite end of said arm is hinged to the car body at s³. A brace s⁴ extends from the lower portion of the end gate to the arm s². An ear s⁵, extends laterally from each upper corner of the end gate far enough to extend across the adjacent bar 36. The relative height of said bars and said ears is such as that when the car comes to said bars from the right, said ears will pass over a rod upon said bars, whereby the end gate is carried horizontally while the car moves downward away from the end gate until the end of the car is open sufficiently for the discharge of its contents. Bars 36 serve to guide the door along a path at an angle to and above the path which it would take were the bars or their equivalents not provided. When the car is released from the curved arms 7, and allowed to move forward, the ears s⁵, slide downward over the 110 115 120 125

left hand standards 37, until the end gate again rests in position upon the car body. To avoid abrupt falling of the end gate, said standards are inclined toward the right, 5 in order that said ears may remain in engagement with said standards until the end gate rests upon the car body.

It will be observed that the bars 36 act 10 positively to open the gate and that dependence is not placed on the weight of the door itself or on the weight of the material within the car for causing the gate to open.

The lever 32, and the shift bar 29, constitute manual means for operating the latch bolt 20. I also provide mechanism for the 15 automatic shifting of the latch bolt by an empty car running toward the right on the return track. A short rock shaft 38, rests in a horizontal bearing 39, adjacent and at 20 right angles to the inner rail O, of the return track. On said rock shaft is a tripping arm 40, which rises into the path of the car wheels. On the other end of said rock shaft is an upright cord arm 41, from the free 25 end of which a cord 42, extends toward the left to and around a guide pulley 43, and thence diagonally forward and toward the right beneath the main track to and around the guide pulley 44, to the shift bar 29, to 30 which it is attached at the left of said pulley.

When an empty car moves toward the right on the return track, the wheels thereof on the inner rail O, turn the tripping arm 40, toward the right, whereby said rock 35 shaft is turned so as to force the cord arm 41, toward the right. This draws the cord over the guide pulleys 43 and 44, the end of said cord which is secured to the shift bar going toward the right and drawing said 40 bar in the same direction and causing said bar to operate for the release of the latch bolt 20, from the quadrant plate 12, just as is done when the lever 32, is drawn toward the right by the hand of the attendant.

45 Thus my apparatus is adapted for the release of the emptied car from the car-stopping member manually or automatically. Whether the operation is manual or automatic, it will be observed that it is desirable that the car engaged by the car-stopping member be released only after the last preceding car has passed backward on the switch and entered fully upon the return track so as to leave a clear way for the next 50 car. By placing the tripping arm 40, adjacent the return track at a proper distance to the right from the switch, the automatic operation can occur only after the empty car is fully upon the return track.

60 This application constitutes a division of

my application for mine car dumping apparatus, filed May 17, 1909, Serial No. 496,560, patented Jan. 24, 1911, No. 982,426.

What I claim is:—

1. In a car dumping apparatus, the combination of a track support, a continuous unbroken track mounted on the said support to be held thereby with all of its parts fixed against movement and with one part intermediate its ends at a longitudinal inclination such that a car upon it will discharge its contents by gravity through one end, a mechanism for engaging a car to resist and temporarily stop its movement along the said inclined part of the track in order to effect dumping and for then permitting it to move onward, and means for automatically opening the end of the car as the car is stopped. 65

70 2. In a car dumping apparatus, the combination of a track support, a continuous unbroken track mounted on the said support to be held thereby with all of its parts fixed against movement, the said track comprising two substantially horizontal parts at different elevations and a short connecting part between them having a longitudinal inclination such that a car upon it will discharge its contents by gravity through one end, and a mechanism for engaging a car to 75 stop it on the said inclined part of the track in order to effect dumping and for then permitting it to move onward. 80

85 3. In a car dumping apparatus, the combination of a track support, a continuous unbroken track mounted on the said support to be held thereby with all of its parts fixed against movement, the said track comprising two substantially horizontal parts at different elevations and a short connecting part 90 between them having a longitudinal inclination such that a car upon it will discharge its contents by gravity through one end, a mechanism for engaging a car to stop it on the said inclined part of the track in order 95 to effect dumping and for then permitting it to move onward, and means adjacent the inclined part of the track for engaging the vertically movable end door of a car and guiding it along a fixed path at an angle to 100 and above that which it would take if not so engaged, whereby the door is opened as the car is moved into inclined dumping position. 105

110 In testimony whereof I affix my signature, in presence of two witnesses,

CHARLES A. GRIFFITH.
